UNITED STATES PATENT OFFICE.

CHRISTIAN REBSTOCK, OF BRIDGEPORT, CONNECTICUT, ASSIGNOR TO HIMSELF, GEORGE ECKART, OF BRIDGEPORT, AND CHARLES DIETTERLIN, OF NEW HAVEN, CONNECTICUT.

DRAWER-PULL.

SPECIFICATION forming part of Letters Patent No. 275,078, dated April 3, 1883.

Application filed August 3, 1882. (No model.)

To all whom it may concern:

Be it known that I, CHRISTIAN REBSTOCK, of Bridgeport, in the county of Fairfield and State of Connecticut, have invented certain new and useful Improvements in Drawer-Pulls, of which the following is a specification.

The invention relates to what are called "drop-pulls," in which the handle is allowed to drop down by turning on an axis, and to hang near the face of the drawer when the pull is not required for use, being drawn up again into the horizontal position when required for use.

15 I make an efficient and tasteful drop-pull with the portion which engages with the drawer formed in two separate parts applied together and maintained efficiently in position against lateral movement, while they are 20 screwed into a sufficient hole produced in the wood. The two parts engage with trunnions on the hinged part. They take hold of the hinged part by simply embracing its trunnions in suitable sockets.

25 The following is a description of what I consider the best means of carrying out the invention.

The accompanying drawings form a part of this specification.

30 Figure 1 is a front view, and Fig. 2 a side elevation, with a section of the drawer-front to which it is attached. Figs. 3 and 4 represent certain portions on a larger scale. Fig. 3 shows the hinged end of the drop part. It is a front elevation. Fig. 4 is a section through a portion. The remaining figures will be described farther on.

Similar letters of reference indicate corresponding parts in all the figures.

40 A is a portion of the wood-work of the drawer.

B and C are two nearly similar portions, constituting together the housing or fixed portion of the drawer-pull, certain portions being 45 designated by additional marks, as A' B', when necessary. The parts A' B' are semi-cylindrical and screw-threaded.

A² B² constitute a flange or bearing-plate which rests against the drawer-front.

A³ B³ constitute together the salient or protruding portion of the fixed parts. 50

The parts B and C are similar each to the other, except that one is provided with a series of slight spurs or projections, b, projecting from the plane of junction into corresponding slight cavities in the other part. These spurs produce no appreciable effect in holding the parts together; but they resist the sliding of the parts B and C one upon the other, and hold the parts correctly placed, 60 while the whole is secured to the wood by the engagement of the screw-threaded portion A' B', which is effected by turning the whole strongly around by any suitable implement. Conical notches are milled or otherwise produced near the front of A³ B³ in the line of juncture. 65

D is the drop part of my drawer-pull, certain portions being designated, when necessary, by additional marks D' D². The portion 70 D' is circular, and of sufficient size to nearly fill the orifice. D² D³ are tapering trunnions formed thereon. D⁴ is the bar or body of the drop.

E is a stout cross-piece or handle, by grasping 75 which the force of the hand may be readily applied to pull the drawer. The compound construction of this handle will be explained farther on.

The two pieces B C, formed, as shown, with 80 the drop part D and attached handle E, constitute the entire device. To apply it a suitable hole is bored in the drawer-front A, and the parts B C are applied together, with the small projections in one engaging in the corresponding cavities in the other, and made to embrace and engage properly the trunnions D² D³ in the small but sufficient notches provided. Thus conditioned, the screw-threaded parts A' B' are properly entered in the wood, and the 85 whole device turned strongly around until it is screwed home. With a little care in starting the screw-thread aright the device can be made to come to rest with the drop D hanging perpendicularly, and consequently with 90 the cross-bar or handle E horizontal. It is now ready to serve for an indefinite period, the drop D, carrying the cross-bar E, being 95

drawn up into a line nearly coinciding with the prolonged axis of the threaded parts A' B' to pull out the drawer, and dropping again into the position represented by the turning 5 of the drop part on the trunnions D² D³ so soon as it is released.

I make the handle E in several parts, (designated by additional marks E' E², &c.) Referring to Fig. 4, E' is an exterior casing of metal; 10 E², a front face, of plate-glass or other transparent material; E³, a piece of metal foil, paper, or other suitable material, carrying any device or printed letters which it may be desired to present, and E⁴ a piece of wood or other 15 suitable material filling the space in the rear of E³ and forming a strong body for the handle.

The body D⁴ of the drop may be firmly joined to the handle or cross-bar E by extending into or through the latter and being provided with sufficient screw-threads.

Fig. 5 is a plan view of the lower part, C, in position for use, with the trunnions of the drop engaged in the notches; and Fig. 6 is a 25 vertical section through both parts B C and a portion of the drop part E. In these figures H is an ornamental washer or escutcheon applied to the drawer-front in advance of the application of my device, and held in place by the latter. The holding-power of the screw-threads of the parts B' C' is aided by an additional bolt, I, washer J, and nut K. These parts, additional to those shown in Figs. 1 and 2, allow the device to be strongly secured in situations where the screw-threaded portions 30 B' C' do not take a firm hold of the wood. It is only essential that the parts B and C shall be firmly held together by the wood, the bolt and its nut and washer being relied on to sustain the force of the pull in opening the drawer. 35 Further modifications may be made by any good mechanic. The proportions and forms of the parts may be changed. The screw-threads on the parts A' B' may be more acute and more extended. They may be milled or otherwise 40 finished sharply, so as to take a very firm hold

on the wood. The part D', instead of being a flat circular portion, as shown, may be spherical, with the axis of motion, which is the line of the trunnions D² D³, passing through the center. The sockets or tapering holes in the parts B 50 C, which receive the trunnions D² D³, need not be in the joint between the parts B C. They may be conical holes reamed or otherwise made with sufficient accuracy in the parts B C, respectively, at right angles to the line of joint, 55 or in any other desired position. Such an arrangement may under some conditions be desirable where the strength of the arrangement shown might be considered insufficient; but the device as shown presents the more tasteful appearance. The trunnions D² D³ may in some cases be cylindrical instead of conical.

I claim as my invention—

1. In a drawer-pull, the screw-threaded portion A' B', face part A² B², and projecting portion A³ B³, formed in two separate portions, with spurs b in one part engaging in corresponding recesses in the other, and with recesses for receiving trunnions on the drop, in combination with a drop having a head, D', 70 and trunnions D² D³, and adapted to serve relatively to each other and to a drawer, substantially as herein specified.

2. The drawer-pull drop described, composed of the shank D⁴, having means to engage it 75 with the fixed portion, in combination with a metallic frame, E', fixed to the end of said shank and inclosing a transparent front piece, E², and a filling, E⁴, with ornaments E³ interposed between the transparent piece E² and filling E⁴, substantially as described.

In testimony whereof I have hereunto set my hand, at Bridgeport, Connecticut, this 1st day of August, 1882, in the presence of two subscribing witnesses.

CHRISTIAN REBSTOCK.
